LIGHTING FIXTURE HAVING A REFLECTOR
WITH A COMPOUND CURVATURE

Edward B. Kirk, New York, N. Y., assignor to
Donald Deskey Associates, New York, N. Y., a
partnership composed of Ralph G. Gulley and
Donald Deskey

Application December 18, 1947, Serial No. 792,468

2 Claims. (Cl. 240—78)

1

This invention relates to a lighting fixture adapted to afford improved lighting, especially lighting of areas which are unequal in two dimensions, such as halls and the like.

In the lighting of halls it has been the practice either to locate light fixtures of relatively low intensity so close to one another that the substantially circular spots of light produced by each fixture will slightly overlap, or else, if higher intensity sources are used, to arrange light shielding means to prevent the light cast laterally from rising higher on the walls than desired.

In the first case, maximum efficiency can evidently be obtained only by limiting the area covered by each fixture to a space which will be equal in both dimensions. This means that the fixtures must be spaced from one another by distances not exceeding the width of the hall. While this procedure may be satisfactory for halls of relatively short length, it is not satisfactory for halls, the length of which is many times the width thereof, such as lengthy corridors and the like. In such cases, there is demanded the provision of a great number of fixtures, each of low intensity. Since the cost of a fixture is by no means proportionate to the luminous intensity of the output thereof, it follows that an arrangement which would allow the employment of a lesser number of fixtures of higher intensity would be less costly.

Additionally, the efficiency of modern light sources is very much greater for units of relatively large size. In the case of the almost universally employed tungsten electric lamps, the output in lumens for each unit of electricity consumed is almost doubled, in passing from the 10 watt bulb adapted to satisfactorily illumine a narrow hall, to a bulb of 200 watts. Therefore a lighting system employing fewer high intensity units would not only be less costly to install, but would be cheaper in power consumption.

If the second alternative method of employing fixtures which yield a coverage greater than the width of the hall be employed, then there will be an unnecessary amount of light emitted in the cross dimension of the hall. While this may be cut off by shades, so that it does not rise to give undesired illumination of the walls of the hall, yet this will result in a loss of efficiency which may more than offset the higher efficiency of the luminous sources.

The ideal light fixture for duty of the type described, would be a fixture in which the normally circular pattern of light distribution would be altered into a pattern of a form wherein the major and the minor axes bear to one another a ratio several times unity. In this fashion lateral coverage of the hall would be only that needed to reach

2

the walls, while longitudinal coverage would allow the use of fewer fixtures, much more widely spaced from one another.

One object of the present invention is to provide a light fixture which shall produce, with high efficiency, a light pattern of the type last described.

Another object of this invention is to provide a fixture wherein the light primarily emitted from a relatively high power source is acted upon by optical reflective devices so that the pattern cast in two perpendicular dimensions is deformed from a circular shape to a shape approximating an ellipse, which shape is conveniently termed elliptical.

15 A further object of this invention is to provide a fixture of the type described, in which the reflection of the light is accomplished in such fashion that light is not merely screened from areas 20 which it is not desired to illuminate, but is actually changed as to path, so that it reinforces the light in a longitudinal direction, thereby affording much higher optical efficiency of the fixture as a whole.

25 A still further object of this invention is to provide a fixture in which two distinct optical reflective systems are provided, each acting at right angles to the other, the one designed to give a narrow beam, and the other to yield a wide-

30 spread beam, but substantially in one dimension only, the over-all light distribution then approaching the theoretically desired elongated rectangular form, by suitable and relatively slight overlapping of beams from adjacent fixtures.

35 An additional object of the present invention is to provide a lighting fixture adapted to efficiently and adequately illuminate relatively narrow and lengthy corridors, and the like, of which fixture the luminous output shall be emitted without substantial wasteful absorption, and yet shall be of a generally elliptical character with respect to the pattern cast upon a plane surface forming the floor of the corridor.

40 Yet another object of this invention is to provide a fixture having the advantages already 45 enumerated, and additionally avoiding the incidence of direct rays from a light source possessing high intrinsic brilliancy, upon the eyes of persons passing along the hall illuminated by a plurality of such fixtures.

Still another purpose of this invention is to provide a lighting fixture for narrow passageways, which shall emit light in a pattern adapted to cover a relatively great length of the passageway, and yet shall emit only sufficient light to cover the width thereof.

3

Other objects and advantages of the present invention will be apparent to those skilled in the lighting art from the following description, and from the drawings hereunto annexed.

The drawings represent, by way of example and not of limitation, one embodiment of this invention.

Figure 1 is a hyperbolic curve showing the general form of the longitudinal reflector of this fixture.

Figure 2 is an elliptical curve showing the general form of the lateral reflector of this fixture.

Figure 3 is a side elevation of the fixture.

Figure 4 is an end elevation of the fixture.

Figure 5 shows a lateral cross-section of an alternative form of fixture.

Figure 6 shows a cross-section of the lamp proper and the supporting light shield covering the same.

Referring to Figure 1, reference numerals 5 and 6 are foci of conjugate hyperbolae, upon the transverse axis 7, only one hyperbola 8 being shown. This is constructed according to the well known equation:

$$\frac{x^2}{a^2} - \frac{y^2}{b^2} = 1$$

the ratio of a to b being determined by the desired longitudinal spread of the light.

Referring now additionally to Figures 3 and 6 it will be seen that in the longitudinal direction the reflector 9 is shaped in the form of a generally hyperbolic curve, as just discussed. This reflector is supported at the central point thereof by a hollow metal tube 10, affixed to the ceiling by a flange 11 and carrying therewithin the conductors (not shown) for supplying electrical energy to the bulb or lamp proper. The bulb 12 is coated over the lower or neck portion thereof with an opaque reflective coating 13. The use of such a reflective coating, usually formed of a metal possessing high reflectivity, is well known in the art. Such coating may be applied either to the interior or to the exterior surfaces of the bulb, and serves both to prevent direct passage of light downwardly therefrom and to increase the luminous flux in an upward direction. Alternatively, a separate reflector independent of, and exterior to the bulb, may be employed for the same purpose.

The bulb 12 is supported by a socket 14, which is mechanically and electrically adapted to receive the base of the bulb. Socket 14 is supported by a hollow metallic tube 15 which is bent upwardly at an outwardly flaring angle, until it reaches the point 16, where it continues inwardly and terminates in a suitable supporting body 17, affixed to tube 10. The electrical conductors pass through flange 11, tube 10 and tube 15, in order to reach the socket 14. From supporting body 17 another tube 18 is downwardly and outwardly flared as far as point 19, when it bends inwardly and terminates at 20. An outer light shield 21 is affixed to the end 20 of tube 18 by means of screws 22. All metal portions above the top of the shield are preferably made with flat black surface finish on the exterior thereof, in order to prevent unwanted reflection therefrom of any stray light incident thereupon. An air vent 23 allows cooling of the bulb.

It is to be understood that the mechanical details just given are purely illustrative, and that other forms of supporting and shielding devices may be substituted for those here shown, provided that the optical functioning thereof is substantially identical.

4

Reference is now made to Figure 2, illustrating a portion of an ellipse. Foci 30 and 31, on major axis 32, with minor axis 33, determine the curve 34, as well known in geometry. The lateral reflector of this fixture is slightly modified from a true ellipse of this character by having the minor axis increased, while keeping the major axis and foci as shown in Figure 2. The exact amount of this alteration can not be precisely stated, as it is dependent upon a number of considerations. Since the light source is never a true geometrical point, the well known reflective properties of an elliptical reflector, giving rays which cross one another, fail to be perfect and precise. The larger the effective source of light, the greater the deviation from a true ellipse, is found to be desirable. Therefore the theoretical equation:

$$\frac{x^2}{c^2} + \frac{y^2}{d^2}$$

wherein $2c$ is the major axis and $2d$ is the minor axis, no longer holds precisely. In the case of the tungsten lamp, the filament of a bare bulb is preferably placed slightly below the theoretical position, with respect both to the elliptical and the hyperbolic reflectors. When a frosted lamp bulb is employed, it has been found that the frosted glass acts as equivalent to a roughly spherical object emitting about 80% of the light, so that in this case the ellipse may be considerably modified in the manner above described. As larger lamps are used, still further modification must be made to maintain high efficiency.

Yet another reason for modifying the true elliptical shape is to allow the hyperbolic and elliptical reflectors to be blended together, where they intersect above the lamp bulb. It has also been found highly desirable, in order that maximum efficiency and correct optical patterns be obtained, to finish the optically active surfaces of both portions of the reflector to a specular, and not a diffusing finish.

Considering now the manner in which light is distributed by this hybrid reflector, it is first to be noted that the bulb shielding structure acts as a light barrier below the reflective system, and since no light is cast directly downward, except such as proceeds from the reflector, the bulb shield tends to cause a spot, immediately beneath the fixture, of decreased illumination, which would be highly undesirable.

In order better to understand how the difficulty just described is overcome in the present invention, consideration may be given to the manner in which each portion of the reflector functions. The hyperbolic portion of the reflector acts, as well known in optics, so that any ray proceeding from one focus is reflected in a fashion as though it proceeded linearly from the conjugate focus. Thus a widely divergent beam in the longitudinal direction of the fixture is obtained. However this does not prevent the formation of a quasi-shadow region directly beneath the bulb housing, in as far as the rays of light proceeding from the hyperbolic reflector portion are concerned.

Attention is now called to the optical operation of the fixture in a lateral direction. This is most conveniently done by considering this portion of the reflector as though it were a true ellipse, the departure from this form previously mentioned not materially altering the action now to be described. The rays reflected from the elliptical portion do not ultimately spread to as great an extent as those coming from the hyper-

bolic portion, so that the fringe of the optical pattern in the lateral direction may be made to coincide with the wall-floor line of the passageway which it is desired to illumine, while the rays proceeding from other portions of the ellipse will cross one another beneath the lamp housing, whereby the portion of the floor directly beneath the fixture will receive, from the elliptical reflective portion, approximately twice the amount of light received by portions of the floor situated laterally from the fixture, and not directly therebeneath. Since the portion thus doubly illuminated is substantially identical with that lying in the quasi-shadow region of light reflected from the hyperbolic portion of the reflector, a compensatory effect is obtained. In practice, due to penumbral effects, actual measurements show that it is possible, by the artifice just described, to obtain a light pattern which is substantially free from any perceptible undesired shadow field. In like manner, shadow effects caused by portions of the bulb supporting elements are substantially eliminated. It is also evident that no direct rays from the bulb proper can strike the eye of a person situated beneath the fixture.

Attention is now called to Figure 5, which is a schematic showing of an alternative method of supporting the lamp bulb within the fixture. In this form the bulb 40 may be provided with a bowl portion 41, through which light reaches the inner reflective surface of ancillary reflective shield 42. However it is preferred to make the portion 41 of the bulb with a completely opaque and reflective coating, so that element 42 may function purely as a shield, keeping direct rays from a person beneath the fixture. In this latter case, the shield may be formed in any suitable decorative shape, if so desired. Element 43 is the elliptical portion of the reflector, which latter is formed substantially identically with the previously described form, having a lateral elliptical portion, and a longitudinal hyperbolic portion, the latter portion not being shown in this figure.

This form of construction allows the lamp bulb to be supported directly in a socket 44, affixed to the ceiling by the element 45, of any convenient form. In this fashion the cost of construction may be somewhat reduced, owing to the much simpler bulb shield. However it has been found, with this type of fixture, that it is extremely difficult to avoid the projection upon the eye of an observer of a brilliant and disturbing spot of light, due at least in part to the brilliantly illuminated uncoated neck portion of the bulb, which is not situated closely enough to the focal points of the reflector system to have light therefrom properly reflected.

From the foregoing description it will be evident that the fixture of the instant invention affords means for efficiently illuminating elongated areas, with minimum loss of luminous flux, and for allowing the placement of fixtures at considerable distance from one another, by proper orientation of the reflectors, so that the axis of the hyperbolic portions thereof lies along the axis of the hall or passageway in which a plurality of fixtures are placed. Furthermore, this fixture provides means for illuminating hallways, whereby the luminous pattern emitted is laterally confined within desired limits, while at the same time the longitudinal extent of the pattern is enhanced to a substantial degree.

A further advantage of the fixture of this invention is that a completely effective shielding of direct light rays is provided at all points illumined

by the fixture, and yet no "blind" spot exists in the field of illumination.

Among the uses of the fixture of this invention are the illumination of areas of all kinds which are of a length great in comparison with the width thereof. This includes display cases, show counters, highways, tunnels and the like. For street lighting the fixture may be tilted slightly, in order to secure a better distribution pattern 10 when not mounted over the middle of the street.

While there have been shown and described certain embodiments of this invention, it is to be understood that these are by way of illustration only, and that various alterations and extensions will become apparent to those skilled in the illuminating art. Therefore the scope of this invention is limited only by the hereunto appended claims.

Having now fully shown and described this invention, what is claimed and desired to be secured by Letters Patent of the United States of America is:

1. An illuminating ceiling fixture comprising in combination, means for supporting a substantially spherical source of light, a shield situated below and at least partly around said light source, means for projecting light upwardly from said source, and a hybrid reflector located substantially horizontally above said source and receiving light therefrom, said reflector having a generally hyperbolic shape in one dimension and having a generally elliptical shape in a dimension at right angles to said first dimension, the relative position of said light source and said hybrid reflector being such that the floor below said fixture is illuminated in a pattern extending in the direction of the conjugate axis of said hyperbola for a distance several times the distance in which it extends in the direction of the minor axis of said ellipse, said light source being provided with opaque means for substantially preventing downward direct projection of light therefrom, and being provided with means of reflective character for re-projecting upwardly light proceeding from said source.

2. An illuminating fixture according to claim 1, in which said elliptical portion of said reflector has the minor axis thereof of a different length relative to the major axis and the foci than for a true ellipse, whereby said light source may be a standard size frosted lamp bulb, while yet maintaining good efficiency of light distribution from said fixture.

EDWARD B. KIRK.
